US00D865062S

(12) **United States Design Patent** (10) **Patent No.:** **US D865,062 S**
(45) **Date of Patent:** **** Oct. 29, 2019**

(54) **DIGITAL SIGNAGE**

- (71) Applicant: **LG ELECTRONICS INC.**, Seoul (KR)
- (72) Inventors: **Hewon Kihl**, Seoul (KR); **Yongho Lee**, Seoul (KR); **Hyeyoung Hong**, Seoul (KR)
- (73) Assignee: **LG ELECTRONICS INC.**, Seoul (KR)

(**) Term: **15 Years**

(21) Appl. No.: **35/504,806**

(22) Filed: **Sep. 21, 2017**

(80) **Hague Agreement Data**

Int. Filing Date: **Sep. 21, 2017**
Int. Reg. No.: **DM/100665**
Int. Reg. Date: **Sep. 21, 2017**
Int. Reg. Pub. Date: **Apr. 27, 2018**

(30) **Foreign Application Priority Data**

Mar. 21, 2017 (KR) 30-2017-0013077

- (51) **LOC (12) Cl.** **20-02**
(52) **U.S. Cl.**
USPC **D20/42**

CLAIM

The ornamental design for a digital signage, as shown and described.

DESCRIPTION

1. Digital signage
- 1.1 : Perspective
- 1.2 : Front
- 1.3 : Back
- 1.4 : Left, the right being a mirror image
- 1.5 : Top
- 1.6 : Bottom

The broken lines depict portions of a digital signage that form no part of the claimed design. The digital signage is shown with a symbolic break in the broken lines. The appearance of any portion of the article between the break lines forms no part of the claimed design.

1 Claim, 6 Drawing Sheets
